UNITED STATES PATENT OFFICE.

JAMES E. MCNEIL, OF LOS ANGELES, CALIFORNIA.

RAIL-ANCHOR

1,165,193.

Specification of Letters Patent. Patented Dec. 21, 1915.

Application filed July 6, 1915. Serial No. 38,130.

To all whom it may concern:

Be it known that I, JAMES E. MCNEIL, a citizen of the United States, residing at Los Angeles, in the county of Los Angeles and 5 State of California, have invented certain new and useful Improvements in Rail-Anchors, of which the following is a specification.

This invention relates to improvements in 10 rail anchors or anti-rail creeping devices for railway rails, and it is an object of the invention to provide a device of this character in which means gripped upon the rail may be so connected with the ties of the road 15 bed as to distribute the anchoring strain over an ample portion of said road bed, to insure a positive holding of the devices and the consequent prevention of any creeping action in the rails.

20 It is also an object of the invention to provide one or more rail gripping members and one or more anchoring straps or bars, which may be fastened to any desired number of ties in the road bed upon either or both sides 25 of the said gripping devices.

In the accompanying drawing forming a 30 part of this specification: Figure 1 is a top plan view of a portion of one side of a railway road bed showing rails thereon and an anchoring or anti-rail creeping means applied thereto. Fig. 2 is a top plan view of 35 one of the rail gripping devices and a portion of one of the securing bars or straps being shown as fastened thereto, and the 40 whole being upon an enlarged scale. Fig. 3 is a vertical transverse sectional view taken upon the line 3—3 of Fig. 2. Fig. 4 is a detail sectional view upon a reduced scale showing a modified form of the rail gripping means.

The device of the present invention is 45 designed to afford an anti-rail creeping device or anchoring means which may be clamped upon a railway rail at any point along its length, without any change or preparation of the rail, and which may be so connected with the road bed, and particularly to the ties thereof that it will be firmly held 50 against any creeping action in the rail, the

holding strain being distributed over a considerable portion of the road bed, whereby no excessive strain comes upon any one particular tie.

The details and features of this invention will now be more particularly described 55 reference being had to the said drawing in which 5 indicates a rail engaging member, 6 bolts for holding the same in place and 7 a strap, bar or rod for anchoring the said member and connecting it with the ties of 60 the road bed. The member 5 is provided with an elongated rail engaging portion having upper and lower flanges 8 and 9 forming a groove to receive the edge of the 65 flange of the railway rail 10. The ends of 65 the said rail engaging portion are formed with apertures therein adapted to receive the bolts 6. The said apertures are so arranged that the bolts 6 will come close to the under 70 surface of the rail, preferably touching the same as shown in Fig. 2. The lower flange 9 is preferably widened near the ends thereof and adjacent to the bolts 6 to give the member a good purchase upon the bottom 75 of the rail and thus more firmly hold the 80 said member in position. The member 5 also has a bifurcated projection 11 the bifurcation extending in a horizontal plane and being adapted to receive the ends or intermediate portions of one or more holding 85 bars or straps 7. The bifurcated projection 11 is provided with suitable apertures at 12 and 13 in the upper and lower portions thereof to receive a bar securing bolt 14. The said bar is also provided with 90 one or more openings 15 for receiving said bolt 14 when it is to be secured in place in the bifurcation of the member 5. The bolts 6 may be secured to the other side of the 95 rail base by any suitable or desired means, and preferably by engaging a rail gripping member 16. The said member 16 is quite similar to the member 5 with the exception of the bifurcated projection thereon, and is provided with an upper flange 17 overhanging the upper portion of the rail base and a lower flange 18 projecting below the said base. The lower flange may be widened

near its end portions if desired in the manner described with respect to the lower flange 9 of the member 5. The ends of the said member 16 are perforated to receive the bolts 6 and nuts 19 are applied upon the ends of the bolts to tightly draw the members 5 and 16 toward each other for causing them to firmly grip the rail flanges. The perforated or eye portions of the members 5 and 16 may also be somewhat strengthened by forming thereon surrounding extension portions 20 and 21 which fit upon the bolts for a short distance inside the rail gripping members, the said thickened or reinforced portions being however, interrupted at 22 and 23 to permit of the bolts 6, touching the under side of the rail.

The gripping means is anchored or secured to the track ties, preferably by a bar, 20 rod or link 7. Such a member is preferably made in the form of a flat bar or strap having one or more perforations for receiving the bolt 14 that secures it to the bifurcated projection 11; and also provided with 25 a series of perforations 24, preferably spaced so as to come opposite the successive ties in the road bed. By driving spikes through said apertures, into the ties the said bar may be securely fastened to the road bed and 30 firmly hold the rail gripping member or members so that the rails cannot move longitudinally.

While each gripping device may have a strap or securing bar 7 extending in opposite directions therefrom to any desired distance, it is generally desirable to use more than one rail gripping member as shown in Fig. 1 of the drawing and to connect the said members by a single bar 7, which is 35 nailed, bolted or otherwise secured to the intermediate ties.

It will be observed that an anchoring means of the type described may be fastened to any desired number of ties according to 40 the strain likely to be brought upon the device and the tendency of the rails to creep at any particular point, grade or location upon a railroad. Of course the anchorage is distributed in this way over a plurality of ties making the anchorage very secure.

It will be understood that the minor details of construction in the formation of the parts may be considerably varied without departing from the spirit of this invention 45 and that the mode of gripping the rail may be altered if desired. Thus as shown in Fig. 4 instead of employing a gripping member like the member 16 above referred to, the bolts as 25 used for engaging the rail may 50 be provided with hooked end portions 26 adapted to catch upon the flange of the rail, so that when nuts 27 are tightened upon the straight ends of the bolts, the hooks will be 55 drawn tightly against the flange of the rail, gripping the same and firmly fastening the

strap engaging member of the device to the other side of the rail.

It will be observed that the parts of the device are exceedingly simple and can be readily applied to the rails of the road by 70 unskilled labor if desired.

The parts can be made cheaply and of any required strength and afford an absolute anti-rail creeping holding means or anchor- 75 age.

It will be evident that a device of this character may be applied to either side of either rail in a railway and that it may be applied at any point along the rails and that as many of the devices may be used as de- 80 sired all within the scope of this invention.

What is claimed is:

1. An anti-creeping rail device for railway rails comprising a tie bar adapted to be secured to a plurality of ties, and one or more rail gripping devices adapted to be connected with the bar at suitable points along its length.

2. An anti-creeping rail device comprising an elongated tie engaging bar adapted to be connected with a plurality of ties and a plurality of gripping devices adapted to be secured at any point upon a rail or rails and means for coupling the same with the tie engaging bar at suitable points thereon.

3. A rail anchoring device comprising a tie engaging bar adapted to extend along the sides of a rail whereby it may be spiked to a large number of ties, gripping jaws adapted to be drawn tightly against the flanges of a rail at any desired point thereon and having a projection adapted to be connected with the said tie engaging bar at either end thereof or at an intermediate point along the length thereof for preventing the slipping of the rail longitudinally.

4. An anti-creeping rail anchoring device comprising gripping members having flanges receiving grooves adapted to fit upon the flanges of a rail, bolts for drawing the said members together and thereby gripping the rail, one of said members having a projection, and a securing bar fastened to said projection adapted to be spiked to one or more ties of the road bed.

5. A rail anchoring device comprising flange engaging members having grooves therein for fitting upon the base flanges of the rail, bolts for drawing them tightly against the rail, one of said members having a bifurcated extension, an anchoring strap adapted to fit in said bifurcated extension, means for securing the said strap therein, the said strap having apertures at suitable intervals whereby holding spikes may be driven through the same into the ties of the railway road bed.

6. A rail anchoring device having a rail engaging member formed with rail receiving flanges and perforated eye portions

and rail engaging bolts engaging said eye portions and also engaging the flanges of the rail for binding the member upon the same, the said member having a lateral projection and an anchoring strap fastened to said projection and adapted to be spiked to a plurality of ties in a road bed.

In testimony whereof, I have hereunto set my hand, in presence of two witnesses.

JAMES E. McNEIL.
